US00D617317S

(12) **United States Design Patent**
Tatara et al.

(10) **Patent No.:** US D617,317 S
(45) **Date of Patent:** ** Jun. 8, 2010

(54) **WIRELESS MICROPHONE**

(75) Inventors: **Yoshihiro Tatara**, Nagano-ken (JP);
Fumio Yuzawa, Nagano-ken (JP)

(73) Assignee: **Seiko Epson Corporation**, Tokyo (JP)

(**) Term: **14 Years**

(21) Appl. No.: **29/342,537**

(22) Filed: **Aug. 26, 2009**

(30) **Foreign Application Priority Data**

May 29, 2009 (JP) 2009-012104

(51) **LOC (9) Cl.** 14-01

(52) **U.S. Cl.** D14/225

(58) **Field of Classification Search** D14/225,

D14/226, 191, 218, 240, 137, 138 AB, 138 R;

Primary Examiner—Paula Greene

(57) **CLAIM**

The ornamental design for a wireless microphone, as shown and described.

DESCRIPTION

FIG. 1 is a top front right perspective view of a wireless microphone showing our new design;

FIG. 2 is a top rear left perspective view thereof;

FIG. 3 is a front view thereof;

FIG. 4 is a rear view thereof,

FIG. 5 is a left side view thereof;

FIG. 6 is a right side view thereof;

FIG. 7 is a top view thereof; and,

FIG. 8 is a bottom view thereof.

The broken lines form no part of the claimed design.
